(57) **CLAIM**

The ornamental design for a vehicle center console, as shown and described.

DESCRIPTION

FIG. 1 is a front left top perspective view of a vehicle center console according to the present invention.

FIG. 2 is a rear right top perspective view of the center console shown in FIG. 1.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines form no part of the claimed design, but are instead included to show environmental structure. The broken lines also form an unclaimed boundary of the claimed design.

1 Claim, 7 Drawing Sheets
